[57] CLAIM

The ornamental design for a clip board for bingo, as shown and described.

DESCRIPTION

FIG. 1 is a right front perspective view of a clip board for bingo showing our new design;

FIG. 2 is a front elevational view;

FIG. 3 is a bottom end elevational view;

FIG. 4 is a right side elevational view, the left side being a mirror image thereof;

FIG. 5 is a rear elevational view; and,

FIG. 6 is a top end elevational view thereof.

The bingo markers depicted by means of broken lines in FIG. 1 have been shown for illustrative purposes only and form no part of the claimed design.

FIG. 2

FIG. 3

FIG. 4

FIG. 5

FIG. 6
